DIGESTER CONTROL

James M. McAlear, Needham, Mass., assignor to
 Mason-Neilan Regulator Company, Boston,
 Mass., a voluntary association of Massachusetts

Application April 25, 1947, Serial No. 743,863

15 Claims. (Cl. 183—61)

1
 This invention relates to the control of pulp digesters more particularly in respect to the relief of gases during the cooking process, and the device embodying this invention is especially suited for use in connection with digesters wherein the sulphate or soda process is utilized.

As is well known to those skilled in the art in the manufacture of paper pulp, a digester is filled with wood chips of a character suited to the product and is then charged with cooking liquor until the major portion of the chips are covered, the liquor being in the form of water to which carbonates, sulphides and hydroxides have been added to provide a caustic solution best adapted for the purpose. Heat is then applied to the mass, either directly by the introduction of steam at the bottom of the digester with or without forced circulation, or indirectly by forcibly circulating the liquor from the digester to a heat exchanger and thence back to the digester, it being desirable with either method to raise the temperature rapidly to a predetermined maximum at which the cook temperature is preferably maintained until the pulp has attained the consistency desired.

It will be understood by those skilled in the art that whether a direct or indirect method of heating is employed, the efficient operation of a digester depends upon penetration of the cooking liquor into all of the chips and that this in turn depends on proper circulation throughout the entire mass. And it has been found that during the heating up process of a sulphate digester, quantities of air, together with volatile substances such as terpine and the like which vaporize as the cooking process proceeds, seriously impede circulation, and that these gases, although in gradually diminishing amounts, continue to accumulate for the balance of the cook. Owing to this accumulation of gases during the cook cycle, the actual temperature of the mass fails to adhere to the vapor pressure-temperature curve of the boiling solution, since the non-condensables and volatile fluids must be replaced by vapors from the boiling solution if the digester temperature is to conform with that of the vapor pressure-temperature curve. Thus the heat input is retarded whether the heat is provided directly by the introduction of steam or indirectly by forced circulation.

With a view to improving circulation, it has been customary to vent the gases from the digester from time to time in an attempt to maintain the digester temperature in correspondence with the vapor pressure-temperature of the liquor,

but there has been a tendency to carry over a portion of the liquor solution together with particles of pulp entrained therewith as well as a substantial portion of the liquor vapors, thereby adding to the load of the apparatus which is used to recover cooking liquor and by-products such as terpine.

It will be understood that in the cooking of wood pulp by the sulphate process, a strainer is required at the inner end of the relief pipe to prevent the carry-over of considerable quantities of pulp, and while the carry-over tendency may be materially decreased by improved venting means, it is not only impracticable to operate without a strainer, but means must be provided for cleaning the strainer when it becomes clogged in order that the gases may be relieved as they accumulate during the cook period. And while automatic means have been provided for blowing out the strainer, so far as known to me such means are largely independent of the gas-off control mechanism and function on a motor driven cyclical basis requiring additional equipment which must be designed for the purpose and adds to the cost of the control mechanism.

It is an object of this invention to provide gas-off and strainer cleanout control mechanism wherein pressure and temperature responsive elements of a differential controller function to operate a valve in the digester relief line to bleed off gases as required to maintain the digester temperature in correspondence with the vapor pressure-temperature of the cooking liquor regardless of the pressure obtaining in the digester, and wherein the same pressure and temperature responsive elements also function to govern valve actuating mechanism, whereby intermittent blasts of steam are applied to the digester strainer for cleaning the same so long as it remains clogged. I have found from extensive tests with successive cooks, wherein various kinds of wood chips were used, that by means of the device embodying this invention, the carry-over of liquor together with particles of pulp associated therewith is negligible. Thus the quantity of fluid to be passed through the liquor recovery system is reduced to a minimum and the load on the terpine recovery equipment is correspondingly cut down, thereby materially decreasing the capacity requirements of that apparatus and accordingly lowering the cost of producing paper pulp. Furthermore, by eliminating protracted clogging of the relief line strainer and ridding the digester substantially continuously of air and other volatile vapors only, a digester

temperature best suited to the process is constantly maintained, gas pockets are prevented, and a maximum circulation of cooking liquor is provided, whereby a high grade pulp may be produced at a minimum cost.

The invention will be more fully understood from the following description when taken in connection with the accompanying drawings, in which:

Fig. 1 is a view partly in diagram showing a controller with associated valves and valve actuating mechanism embodying my invention as applied to a pulp digester of the direct heated type.

Fig. 2 is a front elevation of the operating mechanism of the controller illustrated in Fig. 1; and

Fig. 3 is a detail in section of the valve actuating mechanism shown in Fig. 1.

Having reference to the drawings and particularly to Fig. 1, there is shown a digester 10 having the usual detachable cover 11 at the top to provide for charging the register with wood chips, and having a pipe 12 at the bottom equipped with a hand valve 13 through which cooking liquor may be introduced and the digester filled to a level, for example, as indicated by a dotted line 14. The pipe 12 and valve 13 are also adapted to be used to discharge the finished pulp at the end of the cook.

As herein shown the digester 10 is arranged to be heated directly by the introduction of steam and for this purpose a perforated ring type manifold 15 may be employed which is connected by a plurality of pipes 16 with a steam inlet line 17. The introduction of steam through the line 17, from a source not shown, is governed by a control valve 18 which, as illustrated, is operated pneumatically and is governed by a controller 19 to which it is connected by means of a pipe 20. The controller 19 responds to changes in pressure in the digester 10 through a pipe 21 and serves to vary the digester pressure in accordance with a selected schedule as for example, a schedule wherein the digester pressure is raised from atmosphere to 100 p. s. i. during a period of substantially three quarters of an hour, is maintained at that pressure for approximately three hours, and is then reduced at the end of the cook. For this purpose the time cycle pressure controller 19 may be of any usual construction, and it will be understood that while I have illustrated a time cycle pressure controller for governing steam input, the introduction of heat may be governed by a rate of flow controller or other means if desired.

As the heating up process proceeds, the air which is trapped in the digester after the charging operation is completed, together with other non-aqueous vapors which are released during the process, must be vented if the digester temperature is to conform to the vapor pressure-temperature of the sulphate solution in accordance with the selected pressure schedule afforded by the controller 19. For this purpose the digester is provided with a relief line 25 which is controlled by a relief valve 26 and is arranged to discharge into apparatus, not shown, in which products such as cooking liquor and turpentine are recovered.

It has been found that considerable surging occurs in the digester during the boiling process and that some of the pulp tends to enter the relief line 25. To prevent this, a strainer 27, which may be in the form of a perforated plate,

is provided at the inner end of the relief line. It has also been found that the tendency to surge is materially accentuated by the intermittent release of relatively large quantities of gas and this not only tends to carry over slugs of liquid, but also tends to cause some of the pulp to become impinged against the strainer screen thereby causing the screen to become clogged. It therefore becomes necessary to provide means for gradually bleeding off the air and non-aqueous vapors as they are released, thereby materially reducing the surging tendency and, by reason of the restricted flow through the relief line, lessening the tendency to clog up the strainer. Furthermore, by this method of operation, circulation is improved and the average digester temperature may be made more nearly to adhere to the vapor pressure-temperature of the cooking liquor. And in accordance with my invention I provide automatic means which function as a gas-off control to vent the gases at the rate at which they are released and which also function with a simple form of valve actuating mechanism as an automatic device for cleaning out the strainer whenever it becomes clogged.

The gas-off control consists of a pressure-temperature relation controller 30 which may be of any usual construction, the controller herein illustrated being with slight modification similar to that disclosed in the United States patent to N. Belaef, No. 2,284,795, dated June 2, 1942, and being adapted to actuate the relief valve 26 as required to maintain a set relation between the digester pressure and temperature. The relief valve 26 is preferably of substantially less capacity than the steam valve 18, being sized to take care of the maximum relief gas requirements and when fully open, to have no appreciable affect on the digester pressure. It includes an operating pressure chamber 31 which is partially defined by a diaphragm 32, the pressure in the chamber being opposed by a spring 33 in the usual manner. As herein illustrated, the parts are so arranged that the valve is normally closed, i. e. the valve is opened by an increase in operating pressure. Means for connecting the pressure chamber 31 of the valve with the output pressure on the controller 30 is in the form of a line 34 which is governed by a valve 190, to be more fully described. The controller 30 is responsive to changes in digester pressure through a pipe 36 which is preferably connected to the digester at a point near the connection with the relief line 25 as indicated at 37. It is also responsive to changes in temperature at a point downstream of the strainer 27 by means of a temperature sensitive bulb 38 which is connected to the controller by flexible tubing 39, the bulb being preferably mounted in a side connection 40 with which an elbow 41, forming a part of the relief line, is provided.

Having reference to Fig. 2 of the drawings, the pressure-temperature relation controller 30, which is herein illustrated as of the indicating type, will serve to describe the operating principle embodied in my invention but the controller may be of the two-pen recorder type if desired. The controller mechanism is mounted on a suitable back plate 45 and is provided with indicating pointers 46 and 47 and a setting indicator 48 which are adapted to cooperate with a scale 49. At 50 is an assembly support including a circular portion 51 and an extension 52, the circular portion being rotatably mounted on the back plate 45 by means of a fixed bearing ring 53 and having

a gear segment 54 meshing with a pinion 55 which in turn is mounted on a shaft 56. The shaft 56 may be provided with a squared end suitable for a key, not shown, by which the assembly support arm may be rotated clockwise or in a counter-clockwise direction. The setting indicator 48 is attached to the circular portion 51 and serves to indicate the ratio setting between the digester pressure, and the actual temperature, in terms of pressure, of the vapors being released through the relief line 25 in a manner to be described. The extension 52 may carry a nozzle 60 mounted on a support member 61 made fast to the extension. Cooperating with the nozzle 60 is a flapper 62 in the form of a flat spring secured at one end to a flapper arm 63, as by rivets 64. The flapper arm 63 is pivotally mounted at one end on the extension 52 and at the free end is herein shown as integral with a cam follower arm 66 which rests on a cam 67, to be more fully referred to. The nozzle 60 may extend into an opening 68 in the flapper arm for cooperation with the flapper 62 which is adapted to yield and prevent injury to the parts in the event that the normal operating range of movement is exceeded. While I have herein shown one type of nozzle-flapper arrangement, it will be understood that any usual construction may be employed. A convenient operating fluid, for example air, may be supplied under pressure to the nozzle 60 through the line 34 from a pipe 69 having a restricted orifice 70 supplied from a source not shown. The nozzle-flapper arrangement constitutes a simple form of pressure system for operating the relief valve 26 either directly, or indirectly through a pilot of any standard construction.

The ratio movement by which a selected ratio between the temperature, in terms of pressure, of fluids as they leave the digester and the fluid pressure in the digester may be established and maintained, is comprised essentially of four members which are so arranged in respect to their relative positions and movements as substantially to constitute a parallelogram under all conditions of setting and control. These members comprise an arm 71 rigidly secured to a pivot shaft 72 to which the pointer 47 is also rigidly secured; an arm 73 rigidly connected to the pointer 46 which is in turn pivotally mounted on the shaft 72, and a lever 74 and link 75, the lever being pivoted at one end to the free end of the arm 71 and at its other end being arranged to carry the cam 67, and the link 75 being pivotally connected to the lever 74 and arm 73 as shown. The cam 67 may be adjustably secured to the lever 74 by means of a frictional mounting such as a screw 76 or the like.

The pointers 46 and 47 may be actuated by helical coils 80 and 81, respectively, secured to the plate 45 by supports 82, the former coil being responsive to the digester pressure by means of the pipe 36, and the latter coil being sensitive to the relief gas temperature, which it is desired to maintain at a definite ratio value relatively to the digester pressure, by means of the tube 39 and bulb 38 which together with the coil may be filled with a suitable expansible fluid. The free end of the coil 80 is adapted to rotate an arm 82 which is pivoted on a shaft 83 at the center of the coil and is arranged to move the arm in a counter-clockwise direction on an increase in digester pressure. The pointer 46 may be operatively connected to the arm 82 by a link 84, by which means the pointer is positioned on the calibrated scale 49 in accordance with the pressure in the digester

as maintained by the steam input controller 19. The pointer 47 may be in operative connection with the helical coil 81 by means of an arm 85 and link 86 arranged in a similar manner to the connecting parts just described. The coil 81 positions the pointer 47 over the calibrated scale 49 and is adapted to indicate the relief gas temperature in terms of pressure. The cam 67 and ratio movement, including the pointer arms 71 and 73, link 75 and lever 74, cooperate to position the flapper 62 in relation to the nozzle 60 in accordance with the relative positions of the pointers 46 and 47. As shown in the drawings the cam surface is laid out substantially on the arc of a circle and the cam is positioned in such a way relatively to the lever 74 and the follower 66 that a change in value of the pressure is followed by the same change in value of the temperature in the relief line 25. This is accomplished by a change in output pressure in pipe 34 which results in a change in relief valve opening in a manner to be described. The cam action may be varied by swinging the cam about its mounting 76 or by changing the shape of the cam.

25 The adjustment and operation of the gas-off control is as follows:

The time cycle pressure controller 19 is set to maintain the desired time-pressure cook schedule. The gas-off controller 30 is set to maintain the 30 desired ratio between the temperature of the gases at the bulb 38 and the temperature of saturated vapors of the liquor solution at the pressure in the digester. The last mentioned setting is accomplished by turning the pinion 55 to establish the initial relation between the nozzle 60 and the flapper 62. The rotation of the assembly support 50 counter-clockwise to move the setting indicator 48 from zero on the scale 49 increases the ratio, and as the pointer is turned 35 clockwise and approaches zero, the differential is decreased. A simple method of establishing the ratio setting for a given liquor solution is to set the indicator 48 at a position at which the liquor solution vapors just start to bleed through the 40 relief valve.

45 When the cook is started steam is introduced into the bottom of the digester through the inlet valve 18 as governed by the time cycle pressure controller 19 in accordance with a prescribed time-pressure schedule. In accordance with this schedule, the digester pressure is raised to a predetermined maximum, is maintained at that maximum over a selected period and is then reduced at the end of the cook. As the pressure is raised, air and other non-aqueous vapors collect at the top of the digester and enter the relief line 25. It may be assumed, for example, that the digester pressure is 10 p. s. i. and that the temperature of saturated liquor vapor at 50 10 p. s. i. is 240 degrees F. As air and other non-aqueous vapors enter the relief line 25, the temperature at the bulb 38 will fall below 240 degrees F., the helical coil 81 will wind up turning pointer 47 and arm 71 clockwise, thereby raising cam 67 and flapper 62. The nozzle pressure will thus increase and open the relief valve 26 proportionally to increase the flow of gases from the digester. As the air and volatile vapors escape and are replaced by vapors of the liquor solution, 55 the temperature at the bulb 38 rises, coil 81 unwinds turning pointer 47 counter-clockwise to lower cam 67 and flapper 62 and reduce the opening of the relief valve until the ratio established by the setting pointer 48 is restored.

70 Now let it be assumed that the pressure in the

digester is raised above 10 p. s. i. by the controller 19. As this takes place the pressure responsive coil 80 unwinds turning pointer 46 counterclockwise and with it arm 73, lever 74 and cam 67, thereby tending to raise the flapper to increase the operating pressure and open the relief valve. However, if the temperature at the bulb increases at the same ratio, the temperature responsive coil 81 will also unwind and turn the pointer 47 counter-clockwise so that the arm 71 lowers the cam 67 and tends to reduce the nozzle pressure and close the relief valve. Under the conditions just referred to, the parts are so arranged that the counter-clockwise movement of the cam 67 tending to raise the flapper 62 and open the relief valve is offset by the downward movement of the cam tending to lower the flapper and close the relief valve. Thus so long as the set ratio is maintained, the flapper-nozzle relation remains undisturbed and the opening of the relief valve is not varied. From the above it will be noted that irrespective of the pressure in the digester the opening assumed by the relief valve will remain unchanged so long as the desired pressure-temperature ratio is maintained. And in this connection it will be understood that the correct functioning of the gas-off control mechanism just described is dependent on maintaining a reasonably unrestricted flow of relief gases through the strainer 27, and the device embodying my invention is so arranged and constructed that it also functions to operate a simple form of valve actuating mechanism whereby the strainer is automatically cleaned whenever the flow is sufficiently restricted at that point to interfere with the proper operation of the gas-off control.

Having reference to Fig. 1 of the drawings, I preferably provide a Y connection 90 at the digester outlet beyond the strainer 27. The connection 90 includes a through pipe 91 forming part of the relief line 25 and a side connection 92 which may be at a 45 degree angle thereto. The side connection may be supplied with steam through a pipe 93 at a pressure, for example, of 150 p. s. i. from a source not shown and is arranged to direct steam against the strainer 27 to free it from pulp which has become lodged on the inner surface thereof. A pneumatically operated valve 94 serves to govern the flow of steam through the pipe 93. As herein shown the valve includes a diaphragm 95 partially defining a chamber 96 to which operating fluid under a selected pressure is supplied through a pipe 97 from a source not shown. Fluid pressure in the chamber 96 is opposed by a spring 98, the valve being arranged to be normally closed, i. e. the valve is opened on an increase of operating pressure. When the steam valve 94 is opened to admit a blast of steam against the strainer 27, it is preferable that the relief valve 26 be closed to prevent the passage of steam through the relief line 25 to the recovery apparatus. And the valve actuating means herein illustrated so function in combination with the operating mechanism of the pressure-temperature ratio controller that the pressure and temperature coils 80 and 81, respectively, and their associated parts by which the selected pressure-temperature ratio is maintained, operate also to govern the valve actuating mechanism and thereby clean off the strainer whenever required to maintain the selected ratio.

Referring to Fig. 3, the valve actuating mechanism includes two solenoid valves 100 and 101 which are of the three-way type and are

mounted in the output pressure line 34 from the controller 30 to the relief valve 26 and in the operating pressure line 97 to the steam valve 94, respectively. The three-way valves may be of any usual construction and as herein shown the valve 100 comprises a body having pipe connections 102 and 103 and a bleed connection 104. The valve includes a solenoid 105 which is in operative connection with a valve member 106 which cooperates with two oppositely disposed orifices 107, whereby the bleed connection 104 is closed and operating fluid is permitted to pass through the valve when the solenoid is de-energized, and when the solenoid is energized, fluid flow through the output pressure line 34 is shut off and the pressure chamber 31 of the relief valve is vented to atmosphere. The three-way valve 101 which is operated by a solenoid 108 is of a similar construction. However, the operating pressure line 97 is connected with the valve body as indicated at 109 and 110, the bleed being provided at 111, so that when the solenoid 108 is de-energized, the supply of operating fluid is cut off and the pressure chamber 96 of the steam valve is vented to atmosphere, and when the solenoid is energized, the bleed is closed and the steam valve is opened wide.

Means for governing the operation of the solenoid valves is in the form of a pressure switch 112 which is in turn controlled by the pressure and temperature coils 80 and 81 and the operating mechanism associated therewith in a manner to be described. The switch includes a frame 113 in which a bellows 114 is mounted and is provided at its free end with a T-shaped switch actuating member 115. Surrounding the member 115 is a helical spring 116 which is retained between a head 117 on the member 115 and the lower end of the frame 113 thereby tending to collapse the bellows 114. The member 115, which is slideably mounted in the frame, carries an adjustable switch engaging member 118 at its lower end. A switch member 119 in the form of a leaf spring resiliently engages the adjustment member 118, being rigidly secured at one end to a connection 120. The switch member 119 is adapted to engage a contact 121 which together with connection 120 form part of a circuit whereby the solenoids 105 and 108 may be energized from a source of electric current not shown. By varying the adjustment 118 the switch member 119 may be initially positioned in respect to the contact 121 and thus any desired pressure setting may be provided within the operating range of the device.

The switch 112 is so arranged that it is under the control of the same elements which function to maintain a selected pressure-temperature ratio in the digester. For this purpose the pressure switch bellows 114 is connected with the controller output pressure line 34 by means of a pipe 122. Thus the bellows responds to the same fluid pressure by which the relief valve 26 is operated. It will be understood that the pressure switch member 119 is normally open and that unless the pressure in the bellows 114 exceeds the set value, solenoids 105 and 108 will be de-energized. Therefore output pressure will normally be admitted to the pressure chamber 31 of the relief valve 26 and the operating pressure in line 97 will normally be shut off from the pressure chamber 96 of the steam valve 94. Under these conditions, the relief valve will function and the steam valve will be closed provided the pressure switch is set at a value which exceeds the upper

limit of the overall operating pressure range of the relief valve. If it be assumed that the operating pressure range of the relief valve and steam valve is from 2 p. s. i. when the valves are closed to 14 p. s. i. when the valves are fully open, the switch 112 may be set to energize the solenoids 105 and 108 at a pressure, for example, of 16 p. s. i. Thus unless the output pressure of the controller exceeds the set value, the controller will function to operate the relief valve to maintain the desired pressure-temperature ratio in the digester. Under the conditions just described the operation will be as follows:

The time cycle controller 19 will vary the steam input to the digester to maintain a selected time-pressure schedule throughout the cook period. During this period the relief valve 26 will relieve the gases as they accumulate to maintain the desired pressure-temperature ratio in the digester so long as the relief valve is permitted to govern the flow of gases without interference by the clogging of the strainer 27. Should the strainer become clogged sufficiently to interfere with the flow of gases and render the relief valve ineffective to maintain the required pressure-temperature ratio, the temperature at bulb 38 will fall thereby causing the controller 30 to increase the output pressure proportionally to the increase in the pressure-temperature ratio. When the pressure-temperature differential expands to a value at which an outlet pressure of 14 p. s. i. is provided, the relief valve will be fully opened. If the temperature at the bulb still continues to decrease, the controller will continue to increase the operating pressure to which the bellows 114 is also responsive. When the pressure reaches 16 p. s. i., the pressure switch 119 will engage the contact 121 to close the outlet pressure line 34 and vent the pressure chamber 31 of the relief valve to atmosphere. At the same time the three-way valve 101 will close its bleed connection and will admit fluid operating pressure to the pressure chamber 96 of the steam valve. Thus the steam valve will open wide to admit steam to the strainer 27 and the relief valve will close to prevent the escape of steam through the relief line to the recovery apparatus. The blast of steam into the relief line will not only tend to clean the strainer screen but at the same time will raise the temperature at the bulb 38, and when the temperature at the bulb arrives at a value within the selected pressure-temperature range at which the controller reduces the outlet pressure below 16 p. s. i., the switch 119 will open, thereby closing the steam valve and actuating the valve member of the relief valve to fully open position. Under these conditions if the strainer has been freed by the blast of steam, the bulb 38 will continue to function together with its associated mechanism to vary the opening of the relief valve as required to maintain the selected temperature-pressure ratio. However, should the blast of steam fail to free the strainer, the temperature at the bulb will drop again and the output pressure will build up until the pressure switch is again actuated. The relief valve will again be closed and the steam valve will open to repeat the cycle just described.

It will be noted that the mechanism herein described provides means for controlling the relief of gases from a digester at varying pressures throughout the cook period in accordance with a prescribed schedule, which means also function to provide intermittent blasts of steam against the strainer until it is free of obstructions when-

ever the clogging of the strainer interferes with the effective operation of the gas-off control.

While I have shown and described in detail a preferred form of apparatus embodying this invention, I wish it to be understood that modifications may be employed without departing from the spirit and scope of my invention. And I wish it to be further understood that while I have referred both in the description and in the claims to steam as a suitable medium for cleaning the strainer and for providing an intermittent cleaning action, the term "steam" is intended to refer to any medium having characteristics suited to the purpose.

Having herein described my invention, what I claim and desire to secure by Letters Patent is:

1. In a gas-off control for a digester having heat input means which vary the pressure in the digester, a strainer in the relief line, and a steam line connected to said relief line for directing steam against the strainer from a source of steam supply, the combination with a first valve in said relief line, a second valve in said steam line, a first element responsive to fluid pressure in said digester, a second element responsive to fluid temperature in said relief line, and means associated with said elements for actuating said first valve to maintain the aforesaid pressure and temperature within a selected ratio value, of a third element governed by said first and second elements to close the first valve and open the second valve whenever a relative drop in temperature causes said ratio to deviate from a predetermined value.

2. In a gas-off control for a digester having heat input means which vary the pressure in the digester, a relief line for venting gases from the digester, a strainer in the relief line, and a steam line connected to said relief line for directing steam against the strainer from a source of steam supply, the combination with a first valve in said relief line, a second valve in said steam line, a first element responsive to fluid pressure in said digester, a second element responsive to fluid temperature in said relief line, and means associated with said elements for actuating said first valve to maintain the aforesaid pressure and temperature within a selected ratio value, of a third element governed by said first and second elements to close the first valve and open the second valve when a relative drop in temperature causes said ratio to deviate from a predetermined value, and to reverse the operation of said valves when said ratio returns to said predetermined value.

3. In a gas-off control for a digester having heat input means which vary the pressure in the digester, a relief line for venting gases from the digester, a strainer in the relief line, and a steam line connected to said relief line for directing steam against the strainer from a source of steam supply, the combination with a first valve in said relief line downstream of said strainer, a second valve in said steam line, a first element responsive to fluid pressure in said digester, a second element responsive to fluid temperature in said relief line at a point between said strainer and said first valve, and means associated with said elements for actuating said first valve to maintain the aforesaid pressure and temperature within a selected ratio value, of a third element governed by said first and second elements to close said first valve and open said second valve when a relative drop in temperature causes said ratio to deviate from a predetermined value, and to reverse the operation of said valves when said ratio returns to said predetermined value.

4. In a gas-off control for a digester having heat input means which vary the pressure in the digester, a relief line for venting gases from the digester, a strainer in the relief line, and a steam line connected to said relief line for directing steam against the strainer from a source of steam supply, the combination with a pneumatically operated first valve in said relief line having a predetermined working range of fluid operating pressure change, a second valve in said steam line, a first element responsive to fluid pressure in said digester, a second element responsive to fluid temperature in said relief line, a source of operating fluid pressure, and means associated with said elements for varying fluid pressure from said source to said first valve to maintain the digester pressure and relief line temperature within a selected ratio value, of a third element responsive to said fluid operating pressure as varied by said elements, and means associated with said third element for varying the operating pressure to said first valve and for actuating said second valve to close said first valve and open said second valve when the fluid operating pressure varies from said predetermined working range by a selected value, and to reverse the operation of said valves when said operating pressure returns to said selected value.

5. In a gas-off control for a digester having heat input means which vary the pressure in the digester, a relief line for venting gases from the digester, a strainer in the relief line, and a steam line connected to said relief line for directing steam against the strainer from a source of steam supply, the combination with a normally closed fluid operated relief valve in said relief line having a predetermined working range of fluid pressure change, a steam valve in said steam line, a pneumatic ratio controller having a source of fluid pressure and having a fluid connection with said relief valve, said controller being sensitive to fluid pressure changes in said digester and to fluid temperature changes in said relief line for varying output pressure to said relief valve to maintain a ratio between said digester pressure and relief line temperature within a selected value, a three-way valve in said fluid connection having a normally open through passage and a normally closed bleed, and mechanism for actuating said steam valve, of an element sensitive to changes in said output pressure and in operative connection with said three-way valve and with said steam valve actuating mechanism, said element being operative to close the through passage and open the bleed of said three-way valve, to permit said relief valve to close, and simultaneously to operate said valve actuating mechanism to open said steam valve when said output pressure reaches a selected value, and to reverse the operation of said valves when said output pressure returns to said selected value.

6. In a digester having heat input means, a relief line provided with a strainer for venting gases from the digester, a pipe through which steam may be passed to clean said strainer, in combination, a relief valve in said relief line downstream of said strainer, a steam valve in said steam line, electrical means for operating said valves, a ratio controller sensitive to changes in digester pressure, and sensitive to changes in relief line temperature at a point intermediate said strainer and relief valve, said controller being in operative connection with said relief valve, and varying the value of a valve actuating medium from a source of supply proportionally

to changes in the ratio value of said pressure and temperature to maintain said ratio within a selected value, a switch governing the operation of said electrical means, and an element sensitive to changes in the value of said valve actuating medium operative to actuate said switch when said medium is at a selected value.

7. In a gas-off control for a digester having heat input means for varying the digester pressure, a relief line, a strainer in said relief line, a pipe through which steam may be passed to clean said strainer, in combination, a relief valve in the relief line, a steam valve in the steam line, an element responsive to digester pressure, an element responsive to relief line temperature, said elements being operative to vary the opening of said relief valve to maintain the ratio between said pressure and temperature within a selected value, and means for independently operating said relief valve and for simultaneously operating said steam valve, said means being governed by said elements and operative to close said relief valve and open said steam valve when a relative drop in temperature causes said pressure-temperature ratio to exceed a predetermined value, and to reverse the operation of said valves when said ratio returns to said predetermined value.

8. In apparatus for regulating the venting of gases through a relief line provided with a strainer and extending from a pressure vessel evolving a heated normally gaseous fluid and having a conduit through which steam may pass to clean the strainer, first control means sensitive to the fluid pressure in the vessel upstream of the strainer and to the fluid temperature in the relief line downstream of the strainer for varying the venting of gases through the relief line to maintain the said pressure and the temperature corresponding thereto at a selected differential value, and second control means including an element brought into action by said first control means when said differential exceeds a predetermined value, occasioned by a relative drop in temperature, for admitting steam to said conduit to clean the strainer.

9. In apparatus for regulating the venting of gases through a relief line provided with a strainer and extending from a pressure vessel evolving a heated normally gaseous fluid and having a conduit through which steam may pass to clean the strainer, first control means sensitive to the fluid pressure in the vessel upstream of the strainer and to the fluid temperature in the relief line downstream of the strainer for varying the venting of gases through the relief line to maintain the said pressure and the temperature corresponding thereto at a selected differential value, and second control means including an element brought into action by said first control means when said differential exceeds a predetermined value, occasioned by a relative drop in temperature, for admitting steam to said conduit to clean the strainer, said element being again actuated by said first control means on the return of said differential to said predetermined value for shutting off steam to said conduit.

10. In apparatus for regulating the venting of gases through a relief line provided with a strainer and extending from a pressure vessel evolving a heated normally gaseous fluid and having a conduit through which steam may pass to clean the strainer, first control means sensitive to the fluid pressure in the vessel upstream of the strainer and to the fluid temperature in the

relief line at a point downstream of said strainer for varying the venting of gases through the relief line to maintain the said pressure and the temperature corresponding thereto at a selected differential value, and second control means including an element brought into action by said first control means when said differential exceeds a predetermined value, occasioned by a relative drop in temperature, for shutting off the venting of gases through the relief line and admitting steam to said conduit to clean the strainer.

11. In apparatus for regulating the venting of gases through a relief line provided with a strainer and extending from a pressure vessel evolving a heated normally gaseous fluid and having a conduit through which steam may pass to clean the strainer, first control means sensitive to the fluid pressure in the vessel upstream of the strainer and to the fluid temperature in the relief line at a point downstream of said strainer for varying the venting of gases through the relief line to maintain the said pressure and the temperature corresponding thereto at a selected differential value, and second control means including an element brought into action by said first control means when said differential exceeds a predetermined value, occasioned by a relative drop in temperature, for shutting off the venting of gases through the relief line and admitting steam to said conduit to clean the strainer, said element being again actuated by said first control means on the relative rise of said temperature to said selected differential value for venting gases through the relief line as governed by said first control means and for shutting off steam to said conduit.

12. In apparatus for regulating the venting of gases through a relief line provided with a strainer and extending from a pressure vessel evolving a heated normally gaseous fluid and having a conduit through which steam may pass to clean the strainer when it becomes clogged, differential temperature-pressure control means having a source of valve actuating medium, said means being sensitive to the pressure in the vessel upstream of the strainer and to the temperature in the relief line downstream of the strainer and varying the value of the valve actuating medium proportionally to the difference between said pressure and the relief line temperature corresponding thereto, a valve actuated by said controlled medium for governing the venting of said relief line to maintain said temperature-pressure difference at a selected value, a steam valve in said conduit, and an element actuated by said controlled medium and in operative connection with said relief valve and said steam valve to close said relief valve and open said steam valve when a relative drop in temperature causes the temperature-pressure difference to exceed a predetermined value.

13. In apparatus for regulating the venting of gases through a relief line provided with a strainer and extending from a pressure vessel evolving a heated normally gaseous fluid and having a conduit through which steam may pass to clean the strainer when it becomes clogged, differential temperature-pressure control means having a source of valve actuating medium, said means being sensitive to the pressure in the vessel upstream of the strainer and to the temperature in the relief line downstream of the strainer and varying the value of the valve actuating medium proportionally to the difference between said pressure and the relief line temperature cor-

responding thereto, a valve actuated by said controlled medium for governing the venting of said relief line to maintain said temperature-pressure difference at a selected value, a steam valve in said conduit and an element actuated by said controlled medium and in operative connection with said relief valve and said steam valve to close said relief valve and open said steam valve when a relative drop in temperature causes said controlled medium to vary beyond a predetermined value and to open said relief valve and close said steam valve when said controlled medium returns to said predetermined value.

14. In apparatus for regulating the venting of gases through a relief line provided with a strainer and extending from a pressure vessel evolving a heated normally gaseous fluid and having a conduit through which steam may pass to clean the strainer when it becomes clogged, differential pressure control means having a source of valve actuating medium, a valve in the relief line downstream of said strainer, said control means being sensitive to the temperature in the relief line at a point between said strainer and said relief valve and to the pressure in said vessel and varying the value of the valve actuating medium proportionally to the difference between said pressure and the relief line temperature corresponding thereto, and said valve being normally actuated by said controlled medium for governing the venting of said relief line to maintain said temperature-pressure difference at a selected value, a steam valve in said conduit, and an element actuated by said controlled medium and in operative connection with said relief valve and said steam valve to close said relief valve and open said steam valve when a relative drop in temperature causes the temperature-pressure difference to exceed a predetermined value, and to open said relief valve to vent gases from the relief line as governed by said control means and simultaneously close said steam valve when said difference returns to the predetermined value.

15. In apparatus for regulating the venting of gases through a relief line provided with a strainer and extending from a pressure vessel evolving a heated normally gaseous fluid and having a conduit through which steam may pass to clean the strainer when it becomes clogged, differential pressure control means having a source of valve actuating medium, a relief valve in the relief line downstream of the strainer, said control means being sensitive to the temperature in the relief line at a point between said strainer and said relief valve and to the pressure in said vessel and varying the value of the valve actuating medium proportionally to the difference between said pressure and the relief line temperature corresponding thereto, and said valve being normally actuated by said controlled medium for governing the venting of said relief line to maintain said temperature-pressure difference at a selected value, a steam valve in said conduit, and an element sensitive to the value of said controlled medium and in operative connection with said relief valve and steam valve to close said relief valve and open said steam valve when the controlled medium exceeds a predetermined value, and to open said relief valve to vent gases from the relief line as governed by said control means and simultaneously close said steam valve when said controlled medium is returned to said predetermined value.
